UNITED STATES PATENT OFFICE.

EDWIN J. MURPHY, OF SCHENECTADY, NEW YORK, ASSIGNOR TO GENERAL ELECTRIC COMPANY, A CORPORATION OF NEW YORK.

MAGNETIC REVERSING AND SPEED-VARYING GEAR CLUTCH.

1,394,932.

Specification of Letters Patent.

Patented Oct. 25, 1921.

Application filed March 3, 1920. Serial No. 363,056.

To all whom it may concern:

Be it known that I, EDWIN J. MURPHY, a citizen of the United States, residing at Schenectady, county of Schenectady, State of New York, have invented certain new and useful Improvements in Magnetic Reversing and Speed-Varying Gear Clutches, of which the following is a specification.

My invention has reference to improvements in magnetic reversing and speed varying gear clutches. More particularly, my invention has reference to electromagnetic gear clutching and reversing mechanism by means of which a driving shaft rotating with constant speed in one direction transmits motion to a driven shaft in the same or reverse direction with variable speed. This I accomplish by both revolving and rotating a system of magnetic rollers connected to the driving shaft, on the surface of an annular magnetic toroid connected to the driven shaft. The toroid may be of any suitable type, such as spheroidal, parabolic, hyperbolic, or polygonal, and I do not limit my invention to any particular type. The flux path of an electromagnet is through the toroid and rollers which gives a good frictional clutching engagement between these members. The speed and direction of rotation of the toroid is dependent upon the points of engagement between the toroid and the rollers. The points of engagement may be shifted by moving the toroid in the direction of the driving shaft, and in this manner the driven shaft may be caused to rotate in either direction at the desired speed, or to remain stationary.

In the accompanying drawings, which form a part of this specification, one of the many forms which my invention may assume is illustrated as follows:

Figure 1 is a front elevation, partly in section; Fig. 2 is an end view of Fig. 1; Fig. 3 is a reproduction of a portion of Fig. 1, with the structural dimensions indicated, and Fig. 4 is a perspective view of one form of toroid used with my invention.

Referring to the drawing, a magnetic frame 1, supported by a base 2, has an overhanging annular flange 3 at one end, which forms a housing for a magnet coil 4, which latter is suitably mounted and insulated from the frame, as shown in Fig. 1. The opposite end of the frame, indicated by the numeral 5, is cylindrical and has a central

bore which extends clear through this portion of the frame into said housing and in which is fitted a sleeve 6 of non-magnetic material which serves as a bearing for a cylindrical magnetic member 7. The member 7, which is journaled in said bearing, extends at one end into the housing formed by the flange 3 and the other end extends out of the casing a suitable distance in the opposite direction. The end of the member 7 projecting into the housing passes through the center of the magnet coil 4, thus constituting a magnet core, and terminates in an annular toroid 8, which is convexly curved outwardly from its axis, which latter coincides with the axis of cylinder 5 and of member 7, and it curves toward the edge of the flange 3. The purpose of the annular toroid will more fully appear hereinafter. The toroidal surface shown in the drawing is supposed to be circular in the line of its axial section. This means that it has been generated by the rotation of a segment of a circle about an axis in its own plane. But for the purposes of my invention it is not essential that the toroidal surface be thus generated; it may be generated by the proper rotation of a segment of an ellipse, or of a parabola, or hyperbola, and it may also be formed by the proper rotation of any proper curve that is not a conic section. In fact the conoid might be formed by the proper rotation of a segment of a regular or even irregular polygon. As has been indicated, and as will more fully appear hereinafter, the points of contact of the toroid with certain rollers which will presently be described determine the direction of rotation and the speed of rotation of the toroid and of the driven shaft, and the gradation of speed of the driven shaft is consequently determined by the peculiar surface of the toroid. It will be seen from this that great latitude of choice as to the particular form of toroid is permissible. At its opposite end, the member 7 has a spiral gear 10 keyed or otherwise rigidly secured thereto in any suitable manner, which gear meshes with a pinion 11 of a driven shaft 12. An axial bore 13 extends through the member 7 in which is journaled the driving shaft 14. The latter shaft is driven through gears 15 and 16 by a suitable source of power connected to the shaft 17.

The driving shaft 14 occupies a central position with respect to the toroid 8 and to

the annular flange 3. At its end, projecting through the toroid 8, the shaft 14 has a U-shaped member 18 which supports a pin 19 at right angles to the shaft 14. Two pins 20, 21 are pivotally mounted on the pin 19 by the terminal ears 20' and 21', and the members 20, 21 freely support two rollers or spools 22, 23, which are of magnetic material. The free ends of the members 20, 21 are threaded 10 so that the rollers 22, 23 may be secured in position, washers 24, 25 and nuts 26, 27, being used for this purpose. The ears 20', 21' are each provided with arms 28, 29, respectively, and between them is an expansion 15 spring 30 which holds the members 20, 21 apart and prevents their dropping to the position they would normally assume by gravity, if free to move, and also urges them against the surface of the toroid 8. In 20 case the axis of the toroid is vertically disposed, the spring 30 is not necessary.

The rollers 22, 23 have enlargements 31, 32, respectively, at their outer ends, and these enlargements are arranged to bear 25 frictionally on the edge of the flange 3. The smaller parts of the rollers 22, 23 always bear at some point C on a zone of the toroid 8, such as is indicated by dotted line 8' in Fig. 4, and this point of contact may 30 be shifted by longitudinally moving the member 7. A portion of the cylindrical end 5 of the frame 1 is internally threaded and the member 7 carries a sleeve 33 which is threaded at one end on its outer surface, to 35 fit the internally threaded portion of the frame. A portion of the member 7 is decreased in size forming a shoulder 34 to be engaged by the end of sleeve 33 when the latter is moved. Ball bearings 35 are pref- 40 erably placed between the shoulder 34 and the end face of sleeve 33 to decrease the friction between them. At its opposite end the sleeve 33 is formed as a spiral gear 36 which meshes with a pinion 37, which latter is 45 mounted on a shaft 38, arranged to be rotated by a hand wheel 39, from which a pointer 39' extends over a dial, as indicated. A stop collar 40 is adjustably secured to the member 7 to limit the movement of the 50 sleeve 33 in the direction away from the frame 1. It is, therefore, obvious that the longitudinal movement of the member 7, which determines the point of contact between the rollers 22, 23 and the toroid 8, is 55 accomplished by turning the hand wheel 39 in the desired direction.

By the longitudinal movement of the member 7, as controlled by the hand wheel 39, the toroid is moved forward or backward 60 as the case may be, the rollers 22, 23 always bearing upon the surface of the toroid, while the points of contact are shifted. It should be observed that this shifting of the points of contact of two friction gears, par-

ticularly when they are clutched magnet- 65 ically, should not be effected by sliding one of the members upon the other, since such sliding shift is objectionable on many accounts and particularly because it requires the application of considerable force. In 70 the construction here shown the shifting of the contacts between the rollers and the toroid is accomplished by a rocking motion of either or both the rollers and the toroid and only a small force is required for this 75 purpose.

A good clutching engagement between the rollers 22, 23 and the toroid 8 is secured by energizing the coil 4. The path of the flux thereby set up is through the member 7 80 which serves as the core of the magnet, the toroid 8, the rollers 22, 23, and the enlargements 31, 32, the flange 3, the cylindrical end 5 of the casing, across the small reluctance gap formed by non-magnetic lining 6 to the 85 core member 7. It is desirable to make the gap between the edge of the toroid 8 and the flange 3 as wide as possible in order to diminish there the unavoidable leakage flux, so that practically the whole flux passes in 90 the manner described through the rollers 22, 23 and the enlargements 31, 32.

In operation the driving shaft 14 is rotated with uniform speed which may be assumed to be n revolutions per unit of time, 95 which of course means that the rollers 22, 23 with their enlargements 31, 32 will revolve n times per unit of time about the axis of shaft 14. The magnet coil is kept energized so that the rollers will firmly bear 100 upon some point C on a zone on the surface of the toroid, while the enlargements will bear upon the edge of the stationary element, the edge of flange 3, whereby the rollers are rotated about their axes.

A clear distinction must be made between the movement of the rollers about the axis of the shaft 14 and about their own axes. The movement of the rollers about the axis of the shaft 14 is in the proper and mathematical meaning a revolution; while the movement of the rollers about their own axes is in the proper and mathematical meaning a rotation. The combined revolution and rotation is spoken of in the art as a planetary 110 movement. The effects of the two movements, each separately considered, upon the toroid are quite distinct from each other, and the combined or resultant effect upon the toroid is the gist of this invention, as 115 120 will presently appear.

Referring now particularly to Fig. 3, and designating by a , the distance of the edge of the flange 3, from the axis of the shaft 14; by r , the radius of the enlargements 31, 125 32; by r' , the radius of each of the rollers 22, 23, and by b , the distance of the points C from the axis of the shaft 14: the surface

speed of any of the enlargements, say 32, about axis 14 will be

$$2a\pi n.$$

5 The corresponding surface speed of the roller 23 about its own axis is then

$$\frac{r'}{r}a\pi n,$$

10 and this is at the same time the surface speed in a certain direction which the roller tends to impose upon the toroid at the point C about the axis of the shaft 14.

The surface speed of the roller 23, in its 15 revolution about the axis of the shaft 14 is

$$2b\pi n,$$

and this is also the speed which the roller tends to impart to the toroid at the point C 20 in the opposite direction. The actual or resulting surface speed V of C is consequently

$$V = 2\frac{r'}{r}a\pi n - 2b\pi n.$$

25 This difference may be positive or negative. If it is positive the toroid will be driven in one direction and if it is negative the toroid will be driven in the opposite direction. In this expression b is the only 30 variable quantity and if

$$b = \frac{r'}{r}a$$

the resulting speed of the toroid at the point 35 C is zero. There is always a point on any convex toroid at which

$$b = \frac{r'}{r}a,$$

40 and if the rollers 22, 23 bear upon such points of the toroid the latter will not rotate at all. At any other point on the surface of the toroid b will be larger or smaller

45 than $\frac{r'}{r}a$. If b is larger than $\frac{r'}{r}a$, then the toroid will rotate in one direction and if b is smaller than $\frac{r'}{r}a$ the toroid will rotate in the opposite direction, and the 50 speeds of the rotation will vary in direct ratio with b .

55 It is practicable to determine in advance form of the surface of the toroid required for the desired surface speed of the latter at the different points of contact with the same of the rollers 22, 23; because the quantity b may be computed for any desired surface speed from the fundamental equation, namely:

$$b = \frac{r'}{r}a - \frac{V}{2\pi n}.$$

60 It will be readily understood that numerous details of construction herein described

may be variously changed without departing 65 from my invention.

What I claim as new and desire to secure by Letters Patent of the United States, is,—

1. The combination of a magnetic annular 70 toroid and a driven shaft connected therewith, of a driving shaft and a system of magnetic rollers carried by the same, and an electromagnet coil in position to magnetically clutch the rollers to the toroid. 75

2. The combination of a magnetic frame with a magnetic annular toroid journaled therein and connected to a driven shaft, of a system of magnetic rollers constantly rotated in one direction, and an electromagnet coil in position to magnetically clutch the rollers to the toroid and to the frame. 80

3. The combination of a magnetic frame with a magnetic annular toroid journaled therein and connected to a driven shaft of a 85 driving shaft constantly rotated in one direction and carrying a system of magnetic rollers, an electromagnet coil in position to magnetically clutch said rollers to the toroid and to the frame, and means for shifting the toroid zone of magnetic contact between the rollers and the toroid by rocking, as distinguished from sliding one or both contacting elements with reference to the other. 90

4. The combination of a magnetic frame 95 with a magnetic annular toroid journaled therein and connected to a driven shaft, of a driving shaft constantly rotated in one direction and carrying a system of magnetic rollers, and electromagnet coil in position to magnetically clutch said rollers to the toroid and to the frame, and means for shifting the toroid zone of magnetic contact between the rollers and the toroid. 100

5. The combination of a magnetic frame 105 with a magnetic annular toroid journaled therein connected to a driven shaft, of a system of magnetic rollers constantly rotated in one direction, an electromagnet coil in position to magnetically clutch the rollers to the toroid and to the frame, and means for shifting the toroid zone of magnetic engagement between the rollers and the toroid. 110

6. The combination of a magnetic frame with a driving shaft constantly rotating in 115 one direction and actuating a system of magnetic rollers, of a driven shaft connected to a magnetic annular toroid concentric with the driving shaft and journaled in the frame, an electromagnet coil in position to magnetically clutch the rollers to the toroid and to the frame, and means for shifting the zone of engagement between the rollers and the toroid. 120

In witness whereof, I have hereunto set 125 my hand this first day of March, 1920.

EDWIN J. MURPHY.
